P. W. Wilson
ATTORNEYS.

UNITED STATES PATENT OFFICE

2,303,002

TAG-LINE DEVICE

William Ruddock, South Pasadena, Calif., assignor, by direct and mesne assignments, to The McCaffrey Ruddock Tagline Corporation, Los Angeles, Calif., a corporation of California

Application March 18, 1941, Serial No. 383,968

5 Claims. (Cl. 242—107)

This invention relates to material handling devices, such as crane mechanisms and the like, and particularly to mechanisms for preventing a bucket, or other material engaging device suspended from a boom, from turning or spinning in operation. Such mechanisms are commonly known as taglines.

In order to prevent turning of the bucket, it has been customary to fasten a line to a portion of the bucket and to provide some means for maintaining the line under tension during operation of the crane. In the past, this has been done by the utilization of counterweights sliding on the boom, but such mechanisms are ineffective when the boom approaches a horizontal position. Spring driven reels, attached to the boom, winding the tagline to maintain it under tension have also been used, and work very well. My United States Patent No. 2,166,479, shows one form of spring driven tagline device. This type of mechanism is subject to limitation in use, however, in that any turning effort on the spring in the direction of winding tends to snap or kink the spring. Coiled springs, used to produce a torque, are very easily broken by any torque tending to unwind them, and when the line parts or becomes detached from the bucket, the reel, free of any restraining influence, tends to spin. Because of its high rotational inertia, such spinning will cause it to continue turning after the spring has reached its neutral condition, thus kinking the spring, often so badly that it cannot be removed from the casing, thus rendering the entire device useless.

When lifting magnetic materials with a lifting electromagnet operated by a crane, in addition to the provision of means for preventing the hoisting lines from twisting by reason of the magnet spinning, some provision must be made to prevent the electric cables leading to the magnet from breaking. As the cable is relatively weak, it must be held clear of obstructions, and at the same time, must not be placed under undue tension. Various makeshift methods have been employed in accomplishing this result, none of which are very satisfactory.

It is therefore an object of the present invention to provide a tagline reel which will not be damaged by parting of the tagline.

It is a further object of the present invention to provide a tagline reel which will protect the power cable of a lifting magnet.

It is a further object of the present invention to provide a tagline device in which the tension on the line can be readily increased without the

necessity of coiling the line for insertion over the reel.

It is a further object of the present invention to provide a tagline reel in which the spring can be readily replaced.

This invention possesses many other advantages and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that this detailed description is not to be taken in a limiting sense, since the scope of the invention is best defined by the appended claims.

Figure 1 is a side elevation of part of a crane, showing the device of the present invention in place on the boom thereof;

Figure 2 is an enlarged sectional elevation taken on line 2—2 of Figure 1;

Figure 3 is an enlarged fragmentary section of a portion of the device of Figure 1, taken on line 2—2 of Figure 1;

Figure 4 is a section taken on line 4—4 of Figure 2;

Figure 5 is a section taken on line 5—5 of Figure 2;

Figure 6 is a fragmentary elevation of a portion of the device of Figure 2 in one condition of operation; and,

Figure 7 is a view similar to Figure 6 of the device in another condition of operation.

The device has been shown in Figure 1 as applied to a crane having a boom B and supporting a lifting electromagnet M for handling magnetic materials. It is to be understood, of course, that the device is equally applicable to other forms of lifting or hoisting machines.

In order to prevent the magnet M from spinning and thus tangling the hoisting line L, a tagline T is provided which passes over a sheave S attached to the boom and is maintained under suitable tension by the device with which the present invention is primarily concerned. The power cable for operating the electromagnet M is indicated at C. In operation the reel R maintains the tagline T under tension and thus prevents the magnet from twisting and at the same time protects the cable C against undue tensioning in a manner hereinafter described.

Referring more particularly to Figure 2, and the sections indicated thereon, the device embodies a flanged reel 10 for receiving the tagline

T, and a second flanged reel 11 of less diameter for receiving the power cable C. These two reels may be secured together by any suitable means, but have been indicated as being bolted together as at 12. In order that these reels or spools may be rotated to take in and pay out the electric cable and tagline, they are fixedly secured to a short shaft 13. This has been done by securing the reels to a plate 13' having a hub secured to the shaft by the pin 13''. This shaft 13 is rotatably mounted in a flanged bearing 14 and is secured against outward axial movement by a collar 15 pinned to the shaft 13. The bearing 14 is secured to a housing 16 by any suitable means, as by bolts 17 passing through the flange of the bearing and threaded into the housing 16. This housing 16 may be secured to the boom B by U-bolts 18 and clamps 19, or in any other suitable manner. Thus the bearing 14 and housing 16 are held stationary with respect to the boom B and the reels 10 and 11 are free to rotate with the shaft 13.

Within the housing 16 is mounted a mechanism for producing a torque on the shaft 13 to produce the tension desired on the tagline T. This mechanism consists of a coiled spring 20 one end of which is held against movement under normal operation by the bearing 14 and the other end of which turns about the axis of the shaft 13 upon rotation of the shaft. This has been done in the present instance by the provision of a tube 21 which is mounted for rotation with the shaft 13 by being secured at one end to the collar 15 and the shaft by the pin 15''. The other end of the tube 21 is mounted for rotation on the housing 16. A stub shaft 22 is secured to a plate 23 which is in turn secured to the housing 16 by welding or the like. Secured to the tube 21 against rotation is a bushing 24. This may be done by cutting away the tube 21 and providing a projection 24' on the bushing for engaging the cutaway portion of the tube 21. The bushing 24 is provided with a bore rotatably engaging the stub shaft 22, thus supporting the tube 21 for rotation in the housing.

In order to transmit the torque from the spring 20 to the tube 21 and to the bearing 14 the spring has its ends formed with the hooks 25 and 26, of a form shown in Figures 2, 3, 6 and 7. The bushing 24 and the bearing 14 have projections 27 and 28 for engaging the hooks 25 and 26 respectively. As best shown in Figures 2, 3 and 6, these projections take the form of short portions extending almost to the interior surface of the housing 16, said projections having one end rounded as at 27a and 28a for engaging the hooks 25 and 26 respectively and the other ends 27b and 28b slanting towards the ends of the housing. With this construction it can be readily seen that rotation of the tube 21 in the direction of the arrow in Figure 6 will cause the hooks 25 and 26 to engage the ends 27a and 28a of the projections, but rotation in an opposite direction will cause the disengagement of the hooks from the projections and will permit them to ride past the slanting or outwardly extending portions 27b and 28b thereof. This forms a ratchet and prevents the development of an unwinding torque in the spring 20 thus preserving it from destruction. The spring 20 is of such length that upon insertion in the housing and assembly of the device, it is under some degree of compression, in order to insure that the hooks will engage the projections upon movement of the reel in an un-

winding direction against the tension of the spring.

Thus if the tagline T should break or become unfastened from the bucket, magnet, or the reel, the spinning of the reel under its inertia will not damage the spring but will merely cause the ends of the spring to become unfastened from and ride over the projections. Reverse movement on the other hand will cause the immediate engagement of the hooks on the projections and the development of a winding torque on the reels.

As was previously mentioned, when lifting magnets are used, some provision must be made to protect the power cable during operation of the hoist. As shown in Figure 2 the power cable reel 11 is of a slightly smaller diameter than the diameter of the tagline reel 10. Thus winding of the tagline on the reel 10 is accompanied by a slightly slower winding of the power cable C on the reel 11. The power cable is thus never under tension except that which results from its own weight.

Provision must be made, of course, for connecting the cable electrically to a source of electric current. This has been done by the provision of a pair of insulated collector rings 30 and 31. These collector rings are mounted on the plate 13' with insulating spacers between them and the plate 13, by studs 33 and 34, which are suitably insulated by sleeves and washers in a well known manner. The studs 33 and 34 may serve as connection points for the cable C, as clearly shown in Figure 3.

In order to provide a mounting for brushes 35 which cooperate with the collector rings, a plate 36 is secured to the bearing 14 by the bolts 17. A rod 37, secured to the plate 36, forms a convenient point of attachment for the brush carrier-arms 38, which are secured to said rod for pivotal movement, and are preferably formed of insulating material, and carry brush holders 39 on their free ends. The brush holders are electrically connected to a source of power through insulated studs passing through the plate 36.

In order to protect the brush assembly from the weather and against injury, a housing 40 is secured to plate 36, and extends to near adjacency with plate 13', thus effectively enclosing the entire brush and collector ring assembly.

In order to provide for lubrication of the spring assembly, it is desirable to fill the entire housing with grease or other lubricant. When this is done, it is necessary to provide some means for preventing the lubricant from leaking around shaft 13, to protect the brush assembly from grease. An insulating tube 41 is inserted in a bore of the collector ring assembly, and a spring 42 is inserted in the tube, surrounding the shaft 13. This spring 42 bears against felt packing washers 43, which in turn bear against a shoulder of the shaft 13, and serve to make the space between the bearing 14 and the shaft 13 grease tight.

I claim:

1. A tagline takeup device including a support, a reel mounted for rotation thereon, a coiled spring, means connecting one end of the coiled spring to said support and means connecting the other end of said spring to the reel to cause rotation of said reel relative to said support under the influence of said spring, at least one of said connecting means including means for releasing said spring upon rotation of the reel ahead of the spring and operative to reconnect

said spring upon rotation of the reel in the opposite direction.

2. A tagline takeup device including a support, a reel mounted for rotation thereon, a coiled spring, said spring having a hook on at least one end thereof, means connecting one end of the coiled spring to said support and means connecting the other end of said spring to the reel to cause rotation of said reel relative to said support under the influence of said spring, at least one of said connecting means including said hook and a projection engageable thereby, said hook and projection transmitting the driving torque of the spring but disengaging upon rotation of the reel ahead of the spring and formed to reengage upon rotation of said reel in the opposite direction.

3. A tagline takeup device including a housing, a helical coiled spring having a hook at each end thereof in said housing, a cylindrical element within said coiled spring, a bushing on each end of said housing and said cylindrical element, one of said bushings being fixed against rotation in said housing and the other rotatable therein, a projection on each of said bushings extending to closely adjacent the interior surface of the housing, each projection having one portion formed to engage a hook of the spring, and the other end sloping away from the spring, whereby rotation of the bushings relative to each other in one direction causes engagement of the hooks on the projections but rotation in the op-

posite direction ahead of the spring causes the hooks to disengage and ride past the sloping ends of the projections.

4. A tagline device for protecting a cable comprising a pair of reels mounted for rotation as a unit, a line from one reel to the device to which the cable is attached, spring means driving said reels and maintaining said line under tension, the second of said reels being of less effective diameter than the first reel, and receiving said cable.

5. A tagline takeup device including a housing, a reel mounted for rotation thereon, a coiled helical spring in said housing, said spring having a hook formed on at least one end thereof, means securing said spring at one end to the reel and at the other end to the housing, said means including a projection within said housing extending to closely adjacent the interior wall of the housing, said projection being formed with one end extending at a slant toward the end of the housing and at the other end formed to engage the hook of the spring, said spring being under compression, whereby rotation of the reel with respect to the housing in one direction causes engagement of the hook with the projection, but rotation in the opposite direction past the neutral point of the spring causes the hook to disengage from the projection and ride thereover.

WILLIAM RUDDOCK.
